SHOE OR SIMILAR ARTICLE

George S. Laham, Wichita, Kans.

Application February 7, 1958, Serial No. 49,533

Term of patent 14 years

(Cl. D7—7)

Figure 1 is a rear perspective view of the shoe, or similar article, showing my new design; and

The opposite side has substantially the same appearance.

This application is a continuation-in-part of my earlier application Serial No. D. 39,457, filed December 22, 1955, now abandoned.

I claim:

The ornamental design for a shoe or similar article, as shown and described.
